UNITED STATES PATENT OFFICE.

HUGO GOLDSMITH, OF CINCINNATI, OHIO, AND IRL TUBBS, OF SUPERIOR, WISCONSIN,
ASSIGNORS TO THE P. GOLDSMITH SONS COMPANY, OF CINCINNATI, OHIO, A
CORPORATION OF OHIO.

INFLATABLE ARTICLE.

Application filed April 15, 1925. Serial No. 23,373.

To all whom it may concern:

Be it known that we, HUGO GOLDSMITH and IRL TUBBS, citizens of the United States, residing in the cities of Cincinnati, county 5 of Hamilton, and State of Ohio, and Superior, county of Douglas, State of Wisconsin, have invented new and useful Improvements in Inflatable Articles, of which the following is a full, clear, and exact description, reference being had to the accompanying drawings, forming part of this specification.

Our invention relates to the general class of inflated articles, and particularly to the 15 class of inflated articles comprising inner resilient members usually called bladders and outer coverings usually made of leather or the like. More particularly our invention relates to foot balls, basket balls, volley balls, soccer balls and the like, with which it is 20 customary for players on sides to engage in contests.

It is the object of our invention to provide for such contests, balls, constructed with inner bladders in which valves are disposed 25 which will permit the inflation of the bladders to any desired pressures, and to secure flaps about the valves to hold the valves in predetermined position with relation to holes in uniformly closed covers through 30 which the valves will be exposed for inflation or deflation, as desired. Briefly, therefore, our invention has for its object the provision of laceless foot balls, basket balls, 35 volley balls, pushballs and the like.

In the prior art it has been customary to provide outer coverings for such balls with slits therein which expose tubes on the inner bladders through which the bladders may be inflated and in which the slits may be secured 40 with lacing or hooks in such a way as to draw the sides of the slits together. The difficulties and objections of such structures have been, in the first place, that they never enabled the inflation of the balls to 45 positive predetermined pressures; secondly, that they seldom could be inflated and laced up to allow smooth surfaces over the laced slits in the outer covers, and finally that the valves which usually were open tubes could 50 not be secured tightly, so that frequent re-inflation was required, which during the playing with the balls, resulted in the hardness or softness of the balls being a constantly variable quality.

With balls of our construction it should be 55 possible to definitely establish with the boards controlling the rules, that the balls played with should be inflated to a certain definite pressure which may be easily tested before a game so that the participants will 60 be sure that the ball with which they are playing has been inflated to the regular standard.

Referring to the drawings in which we have illustrated the embodiment of our invention as applied to a round ball such as 65 a basketball:

Figure 1 is a perspective view of the laceless ball.

Figure 2 is a cross section considerably 70 enlarged taken along the lines 2—2 in Figure 1.

Figure 3 is a cross section in a similar position to that of Figure 2, with a different 75 type of valve employed.

Generally indicated at 1 is the outer cover of the ball which as noted, will usually be made of leather. The leather is cut into sections and stitched as shown at 2. Within the outer cover is the bladder 3 usually made 80 of resilient rubber. A hole 4 permits the insertion of the valve 5 which in the illustration shown in Fig. 2 is one of the well known Schraeder type, although other types will serve equally as well. Instead of being secured at the outlet side of the valve, as is customary in pneumatic inner tubes of tires for automobiles or the like, the valve is 85 secured to the bladder at the inlet side of the valve so that the stem projects within 90 the bladder instead of being disposed outside of it. The valve stem is threaded as shown and the locking plates 6 are adapted to secure the valve to the bladder. Instead 95 of binding the two locking plates together on opposite sides of the bladder a leather flap 9 with a hole in it of equal size as that in the bladder is disposed on the outer side of the bladder so that when the locking members are drawn together an air tight seal 100 is made between the inside of the bladder and the outside of the flap. The flap is then stitched as shown at 7 to the outer cover member and a hole 8 in the outer cover provides an easy access to the valve for infla- 105 tion or deflation as desired.

Modification of the particular structure described will readily occur to those skilled

in this art. For example, the inner locking member need not be threaded on the stem but it may be an integral projecting flange from the side of the stem. Also as noted, 5 any type of valve which does not leak may be used instead of the Schraeder type. Another valve type, of rubber construction, is shown in Figure 3 in which type the stem 5 is vulcanized directly to the inner bladder 10 so that no locknut is needed. The outer locknut is, in this type, an integral rubber flange on the stem so that both the locknuts 6 are avoided. The joint where the flap 9 is seamed about the valved stem need not be 15 tight as the stem is an integral piece with the bladder and the only way air can leak out is through the valve. This is prevented in this type of valve by air pressure within the bladder pressing against the turned 20 down walls of its stem and thus holding the air passage through the stem closed.

With the aperture providing access to the valve for inflation there is no necessity of any other apparent opening in the cover 25 and the stitching may consequently be done so that the ball appears uniformly closed throughout all of its seams. The outer surface is therefore entirely uniform and the rebound of the ball is not subject to variations because of a closing flap producing an 30 irregularity in the cover.

Having thus described our invention, what we claim as new and desire to secure by Letters Patent, is:

1. A ball comprising an inner resilient member and a laceless outer cover member with the laceless outer cover member composed of panels permanently stitched throughout with an aperture in the outer cover member and a valve in the inner member and means for maintaining the apertures in permanent alignment. 35

2. In a covered inflatable ball, the combination of a cover formed of stitched sections of covering material, and a bladder 40 having a valve therein, said bladder secured immovable to the inside of the covering material, and said covering material having a hole therein of a size only sufficient to expose the valve, for inflating. 45

3. An inflatable ball having a covering formed of pieces of covering material stitched completely together, a bladder within the ball secured immovably in place therein the covering having a hole intermediate 50 the juncture of the stitched sections, a valve in the bladder held against said covering about the hole, and the hole being of a size merely to make the valve accessible to an inflating device. 55
